UNITED STATES PATENT OFFICE.

FRED A. C. SKINNER, OF ST. LOUIS, MISSOURI.

AIR-HEATING STOVE.

1,416,900.

Specification of Letters Patent. Patented May 23, 1922.

Application filed July 27, 1921. Serial No. 487,930.

To all whom it may concern:

Be it known that I, FRED A. C. SKINNER, a citizen of the United States, residing at St. Louis, State of Missouri, have invented 5 certain new and useful Improvements in Air-Heating Stoves, of which the following is a specification.

The present invention is directed to improvements in air heating stoves, and has 10 for its object to provide a simple construction of stove which will present a maximum heating surface to the air currents traversing the outer casing of the stove and at the same time cause the body of air to take up 15 or absorb the greatest number of heat units from the heating surfaces before the same is discharged from the casing. The improvement herein lies principally in the specific character of the retarding and air deflecting 20 formations against which the currents of air are obliged to impinge in their passage through the chamber of the casing, together with the hot air circulating pipes leading to the flue where the waste gases give up 25 most of their heat before discharging. Further advantages will fully appear from the following detailed description in connection with the accompanying drawings, in which—

30 Figure 1 represents a combined front elevation and transverse vertical section of the outer casing showing in elevation the stove within the casing; Fig. 2 is a middle vertical longitudinal section through the stove 35 and outer casing; Fig. 3 is a horizontal section on the line 3—3 of Fig. 2 through the outer casing, the stove being shown in plan; and Fig. 4 is a rear elevation of the stove with the casing in section.

40 Referring to the drawings, 1 represents a conventional form of coal burning stove provided with a feed charging mouth 2 closed by a door 3, a grate 4, and ash compartment 5 with the usual door 6 as well understood in 45 the art. The stove proper is preferably made in sections as shown (Fig. 2) for purposes of hauling and shipping, the end of one section being received by a recess or offset formed in the contiguous end of an adjacent section as fully indicated in Fig. 2, whereby an air-tight joint is formed between the sections. The stove is surrounded by an outer casing or jacket 8 which is formed at the bottom in the rear of the 55 stove with an extension or scroll 8' for the housing of a suitable circulating fan or

blower F, the same being directly connected to the shaft of electric motor M mounted on the scroll 8'. The upper end of the casing 8 has leading therefrom a series of air-distributing pipes 12, the connections between the air pipes being made so as to provide an air-tight joint to prevent the escape of the hot air from the casing except by way of the pipes 12.

60 In the present embodiment of my invention the outer walls of the stove are provided with a series of spines or teats 13 disposed radially from the body of the stove and extending partially across the hot air 70 chamber C between the stove and outer casing 8; the spines being preferably cone-shaped and tapering outwardly as shown. The spines 13 as formed tend to impart a rotary or turning movement to the air particles impinging against them, this rotary motion tending to thoroughly churn the air and bring a maximum quantity of the air 75 particles into contact with the heat radiating surfaces of the spines, so that by the 80 time the air currents reach the intake ends of the distributing pipes 12 the air has become thoroughly heated and ready for distribution through the pipes to any suitable points of consumption. The spines may, of 85 course, take on other forms such as pyramidal, prismatic, cylindrical, elliptical, bulbous, and the like, without a departure from the nature or spirit of my invention, though the conical shape as here shown is to be preferred. The fuel charging mouth 2 necessarily extends across the hot air chamber 90 C through the casing wall to permit the introduction of the fuel into the fire pot of the stove.

95 The stove is provided with a conical baffle plate 14 disposed across the combustion chamber of the stove, near the top thereof and just below the dome 1', said baffle being secured to the stove wall by four brackets 15 so as to leave an annular space a between the baffle and said wall. As the hot gases rise in the combustion chamber they will be deflected by said baffle to the walls 100 of the combustion chamber licking said 105 walls and the dome 1', and imparting their heat thereto for radiation into the hot air chamber C. Thus a greater part of the heat of the combustion gas will be radiated from the stove before leaving the combustion 110 chamber. The waste gases pass out of the stove at one side of the dome 1' into a dis-

tributing head 16, thence to branch pipes 17, 17 on opposite sides thereof, and downwardly alongside the stove through smoke pipes 18, 18 spaced from the stove, after which the gases enter the flue 19 through cross-pipes 20, 20. Thus the waste gases are caused to traverse a complete circuit of heat-radiating pipes within the hot air chamber C where their heat is radiated to said chamber, the gases being comparatively cool when leaving the flue 19, which is also in the hot air chamber.

The bottom of the flue 19 is provided with a clean-out box 21 above the scroll 8', said clean-out having a cover 22 which may be removed from time to time for the purpose of drawing out the soot and fine ash that is carried into the flue and pipes 18, 18.

The outside air is drawn into the casing 20 by the fan F and then circulates through the casing chamber C as indicated by the arrows in Fig. 2, the air particles becoming thoroughly heated by contact with the walls of the stove, smoke pipes, the spines 13 and 25 the inner walls of the casing. Preferably, the spines are cast in horizontal rows (Fig. 1) the spines of one row alternating with the spines of an adjacent row so that they will be in staggered relation. Features shown in 30 the drawings but not alluded to are well

understood in the art and require no description in the present connection.

Having described my invention, I claim:

In an air heating stove, an inner stove, an outer casing spaced therefrom and forming 35 an air-circulating chamber therewith, an outlet from the casing, a series of air deflecting spines radiating from the body of the stove and extending partially across the space between the stove walls and the outer 40 casing for imparting their heat to the air and imparting a rotary motion to the air particles for thoroughly mixing the same, a conical baffle plate within the combustion chamber of the stove and spaced from the 45 walls thereof for deflecting the gases of combustion against said walls, means for causing a circulation of air through the air chamber, the stove having an outlet for the waste gases at the top, a distributing head 50 communicating with said outlet, pipes extending downwardly from said distributing head, and a flue between said pipes for receiving the waste gases, said distributing head, pipes, and flue being located in the air 55 chamber.

In testimony whereof I hereunto affix my signature.

FRED A. C. SKINNER.
